DOORCATCH

Francis H. McCormick, Glen Ellyn, Ill., assignor
to Edison General Electric Appliance Company,
Chicago, Ill., a corporation of New York

Application August 23, 1932, Serial No. 630,045

2 Claims. (Cl. 126—194)

My invention relates to catch mechanism for doors and the like, more particularly for oven doors, and has for its object the provision of an improved device of this character.

5 More specifically, my invention relates to catch mechanism for drop oven doors of electric ranges which are arranged to swing about a horizontal axis, and contemplates the provision of improved means for latching the door in its closed position, arranged so that all parts of the catch mechanism are concealed thereby enhancing the appearance of the oven.

In carrying my invention into effect in one form thereof, I provide suitable latching means cooperating with a member carried by the door and arranged to engage it when the door is moved to its closed position so as to hold the door closed. In the specific form of my invention disclosed, this member engaged by the latch is an integral 20 part of the hinge mechanism provided to pivotally support the door. The catch mechanism including the latch and the member engaged thereby are arranged so as to be completely concealed by the front walls of the oven.

25 For a more complete understanding of my invention reference should be had to the accompanying drawing in which Fig. 1 is an elevation of an electric range provided with a door catch embodying my invention; Fig. 2 is a fragmentary 30 sectional view of the range of Fig. 1 illustrating the door catch arranged in accordance with my invention; Fig. 3 is a fragmentary view of the range of Fig. 1, portions being broken away so as to illustrate certain structural details; Fig. 4 is a 35 fragmentary sectional view of the range of Fig. 1, but illustrating the catch mechanism in an operative position different from that shown in Fig. 2; and Fig. 5 is a view similar to Fig. 4, but illustrating the catch mechanism in still another 40 operative position.

Referring to the drawing, I have shown my invention in one form as applied to an electric range although obviously any form of heat may be used. As shown, the range is provided with 45 an oven compartment 10 on the right-hand side, as viewed in Fig. 1, and a broiling compartment 11 below the oven compartment. On the left-hand side of the range, a cooking top 12 is provided and beneath the cooking top is arranged a 50 suitable service drawer 13. Suitable electric heating elements (not shown) are provided for the oven broiler and cooking top.

The oven heating chamber is defined by a pair 55 of side walls 14 and 15, an end wall (not shown), top and bottom walls 16 and 17 and a front wall

18. The front wall 18 is provided with an opening 20 whereby access can be had to the oven. This opening normally is closed by a suitable door 21. The top, bottom, side and end walls of the oven are formed from a pair of spaced metallic linings between which a suitable heat insulating material such as rock wool is placed. The door 21 also is formed from a pair of spaced metallic linings between which a similar insulating material will be placed.

The oven, broiler, cooking top and service drawer are supported on a suitable base or frame 22 which in turn is supported in an elevated position on suitable legs 23.

The door 21 is hinged to move about its lower 15 horizontal edge so that it may be swung from a vertical closed position (Figs. 1 and 2) to a horizontal open position (Fig. 5). The door is further provided with suitable means for counter-balancing its weight when being moved between 20 these positions. Preferably, the hinge and counter-balancing means will be arranged in substantially the same fashion as described and claimed in my U. S. Patent No. 1,809,715, dated June 9, 1931.

As there described, the hinge structure comprises a pair of hinge brackets 25, each of which is of bell crank shape. As shown, each bracket is formed of a pair of arms 25a and 25b joined by an arc-shaped arm portion 25c. The arm portions 25a are secured to the door in any suitable manner, as by means of welding, whereas the arm portions 25b project inwardly from the door at substantially right angles to the plane of the door.

It will be observed that the bell cranks 25 are pivotally mounted at their apexes upon a hinge rod 26 which is disposed crosswise of the oven opening and slightly below the surface of the oven floor. The rod is supported at its ends by 40 any suitable means such as clip members 27. The brackets 25 are provided with bearing seats 28 arranged to seat upon the hinge rod 26. The arcuate portions 25c of the brackets are received in apertures or elongated slots 29 provided for 45 them in the door frame. The arms 25b are provided with a latch-like projection 30 arranged to engage a suitable stop 31 when the door is in its open position (Fig. 5).

The arms 25b serve to mechanically connect the 50 door with its counter-balance. This counter-balance, as shown, comprises a strip-like spring 32 secured at its central portion to the lower of the two bottom walls 17 of the oven. As shown, each end of the spring is mechanically connected 55

with the hinge bracket 25 positioned at that end of the oven. These connections are effected by means of vertically disposed links 33. The end portions 32a of the spring member 32, as shown, 5 are turned vertically upwardly and these portions are secured to the lower ends of the links 33 by means of suitable studs 34 attached to the links and passed through suitable apertures provided for them in the upturned ends of the spring. The 10 upper ends of the links are provided with similar stud-like members 35 which are received in apertures 36 provided for them in the arms 25b of the brackets 25.

It will be observed that by reason of these 15 connections the spring 32 is mechanically connected with both of the hinge brackets 25 in such manner that it will serve to counter-balance the door throughout both its opening and closing movements. Thus, when the door is opened the ends 20 of the spring will be moved upwardly tensioning the spring, whereas when the door is closed the spring in returning to its closed door position (Fig. 3) will assist in closing the door.

As previously pointed out, it is a very important 25 object of my invention to provide improved catch means for holding the door 21 in its closed position. This catch means comprises latching members which engage members attached to and movable with the door. The catch means, as shown, 30 comprises a pair of latch members 40 which are pivotally secured adjacent the respective brackets 25. Each latch 40 is pivotally mounted on a pin 41 which in turn is supported by the lower of the walls defining the bottom 17 of the oven. As 35 shown, the pin 41 is received in a suitable bushing 42 provided for it in the bottom wall, the bushing, as shown, being provided with an aperture 43 through which the lever 40 is passed. Preferably, the lever 40 will have a substantially 40 U-shaped cross-section, and will be pivotally secured substantially mid-way of its length to the bushing 42. At its upper end the member 40 carries a roller 44 which as shown is arranged to rotate on a suitable pin 45, the ends of which are 45 supported in the opposite sides of the U-shaped channel member 40. As shown, the base of the U-channel adjacent the roller 44 is cut away so as to avoid any interference between the member 40 and the rotation of the roller.

50 Each latch 40 is so positioned relative to the path of movement of the adjacent bracket arm 25b that when the latch is in one position and the door is moved to the closed position (Fig. 2), the roller 44 carried by the catch will engage the 55 latch portion 30 of the bracket to hold the door closed. The arm 40 is biased to this latching position by means of a suitable compression spring 46 which, as shown, is interposed between the lower end of the arm 40 and a suitable stop or 60 abutment 47 secured to the bottom of the oven.

It will be observed that the catch mechanism is so arranged that when the door nears its finally closed position, the brackets will engage the rollers 44, and that when the door is fully closed 65 the rollers 44 will have slipped over the edges of the latch portions 30 so as to exert a latching or holding action on the brackets and hence will function to hold the door tightly closed.

70 It will be understood that while the springs 46 will be sufficiently strong to effect a positive holding action on the door in its closed position, they will not unduly hinder or prevent the opening of the door.

75 It will be observed that when the door is being moved to its closed position and when it first en-

gages the rollers 44 (Fig. 4), the motion of the door will be retarded, that is, unless additional pressure is applied, the door will remain slightly open, the door being held in this ajar position by the action of the counterbalance spring 32. This provision of means whereby the door can be held slightly open is important in that it provides means for airing out the oven which is desirable especially during broiling operations, and the like.

It will be understood that when the door is in this ajar position (Fig. 4), if it be desired to close the door, it is merely necessary to apply an additional pressure which will allow each roller 44 to snap or roll over the associated latch 30 to its positions shown in Fig. 2 so as to lock the door closed.

The door 21 is provided with a suitable pendant type handle 48 whereby it can be conveniently moved between its open and closed position. The 20 broiler and service drawer are provided with similar handles 48.

In addition to the foregoing advantageous features, my door catch possesses the advantage that all parts of the mechanism are concealed. It 25 will be observed that the members 25b, that is, the arms of the hinge brackets that are engaged by the latch members are completely hidden by the oven door and its surrounding frame, and that the latch mechanism comprising the levers 30 40 and rollers 44, the springs 46 and their abutments 47 are arranged behind the front wall of the oven. This greatly improves the appearance of the range.

While I have shown a particular embodiment of 35 my invention, it will be understood, of course, that I do not wish to be limited thereto since many modifications may be made, and I, therefore, contemplate by the appended claims to cover any such modifications as fall within the true 40 spirit and scope of my invention.

What I claim as new and desire to secure by Letters Patent of the United States is:

1. An oven comprising walls forming a heating chamber having a front opening therein, a door for closing said opening, hinge means pivotally mounting said door for swinging motion from a vertical closed to a horizontal open position comprising a bell-crank hinge arm, means securing said door to one arm of said bell-crank hinge arm so that said door is secured to one side of the pivotal axis of said bell-crank hinge arm, the other arm of said hinge arm projecting inwardly of said door substantially at right angles thereto, catch means arranged to engage the end of said projecting arm comprising a lever behind the front wall of said oven pivotally mounted intermediate its ends, a roller carried by one end of said lever arranged to be moved into the path of movement of the associated inwardly projecting arm, a spring engaging the other end of said lever biasing said roller into engagement with said arm to hold said door in its closed position and a stop for limiting the motion of said lever so as to position said roller in the path of movement of said projecting arm whereby when said door has been moved substantially to its closed position, said roller engages said arm so as to hold said door after it has been closed.

2. An oven comprising walls forming a heating chamber having a front opening therein, a door for closing said opening, hinge means pivotally mounting said door for swinging motion from a vertical closed to a horizontal open position comprising a pair of bell-crank hinge arms, means se-

curing said door to corresponding arms of said bell-crank so that said door is secured to one side of the pivotal axes of said bell-crank, the other arms of said bell-crank projecting inwardly of 5 said door substantially at right angles thereto, catch means arranged to engage the free ends of said last mentioned arms comprising a pair of levers below said heating chamber and behind the front wall of said oven pivotally mounted in- 10 termidate their ends, a roller carried by one end of each of said levers arranged to be moved into the path of movement of the associated inwardly

projecting arm, a spring engaging the other end of said lever biasing said roller into engagement with said bell-crank arm to hold said door in its closed position and a stop for limiting the motion of said lever so as to position said roller in the path of movement of said projecting arm whereby when said door has been moved substantially to its closed position, said roller engages said arm so as to hold said door after it has been closed. 5
